CLAIM

The ornamental design for an enclosure for an electronic communications device, as shown and described.

DESCRIPTION

FIG. 1 is a front, top, and right-side perspective view of an enclosure for an electronic communications device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, right-side, and rear perspective view thereof; and,

FIG. 9 is a front, top, and right-side perspective view thereof, with the door thereof in an open position.

The broken lines depict portions of the enclosure for an electronic communications device that form no part of the claimed design.
